FOUNTAIN MOP

Filed July 19, 1928

Inventor
Eros Westz

Attorney

UNITED STATES PATENT OFFICE

ENOS WERTZ, OF SALEM, VIRGINIA

FOUNTAIN MOP

Application filed July 19, 1928. Serial No. 293,891.

This invention relates to fountain mops and has for an object to provide an article of the kind embodying new and improved features of construction.

5 A further object of the invention is to provide an article of the kind having new and improved features insuring more complete and uniform distribution of the water throughout the body of the mop.

10 A further object of the invention is to produce a mop of desirable shape and relation of parts to adapt it to its particular work.

With these and other objects in view, the invention comprises certain novel parts, elements, units, combinations, constructions, contours and arrangements as disclosed in the drawings together with mechanical and functional equivalents thereof, as will be hereinafter more fully described and claimed.

20 In the drawings:

Figure 1 is a view of the improved mop in elevation.

Figure 2 is a sectional view of the mop taken on line 2—2 of Figure 1.

25 Figure 3 is a transverse sectional view of the mop taken on line 3—3 of Figure 2.

Figure 4 is a transverse sectional view taken on line 4—4 of Figure 2.

30 Figure 5 is a view of the nozzle partly in elevation and partly in section, taken from the side and point of view as indicated by arrow at Figure 2.

Like characters of reference indicate corresponding parts throughout the several 35 views.

The improved mop which forms the subject matter of this application is adapted to be attached to a source of water supply under pressure, as for instance to a hose, and for that purpose a handle part 10 of tubular construction is provided with a hose connection 11. It is to be understood, of course, that the invention is in no way limited to a hose connection of the type and may embody any form of connection found expedient. Also the showing of the relative lengths of the tubular handle 10 to the other parts is no limitation as the handle part may be made of any length found desirable.

50 To the handle opposite the connection a

fitting 12 is secured in any approved manner as by being screw-threaded to the handle part 10, it being understood, however, that it is within the scope of the present invention to form all of these parts integral, and that the showing of the threaded connection is merely for the purpose of making use of merchandisable products.

The fitting 12 is provided with a cylindrical tube 13, preferably belled at the end or flared out as indicated at 14. Within the tube 13, a second tube 15 is secured with an annular space 16 entirely about the inner tube 15 and within the outer tube 13. Both of these tubes are either secured rigidly to or formed integral with the fitting 12 and in either case also spacers 17 are preferably employed for maintaining the annular relation of the tubes 13 and 15. The tube 15 is provided adjacent to the fitting 12 with a plurality of perforations 18 which form communication between the interior of the tube 15 and therefore with the interior of the fitting 12 and the annular space 16 above referred to.

Within the inner tube 15 a hank of cordage 19 is inserted, being compressed to as great a degree as convenient when inserted, and a fastening member 20 having the general characteristics of a nail with a head 21 abutting against one side of the outer tube 13 and extending diametrically through both of said tubes and through the fold of the hank 19. Upon the exterior of the tubular member and fitting, other cordage is applied by folding hanks as shown at 22 with binding cords 23 securing said hanks in circular relation entirely enveloping and surrounding the fitting and hanging down and surrounding the inner hank 19, all of said cordage and hanks being sewed together and bound in any approved manner as by the several stitchings 22 and windings 23.

The fitting 12, as will be noted, is an angular fitting so that the handle 10 is at an inclination to the major axis of the mop as completed, making the completed structure one of such shape as to readily adapt itself to the cleaning of articles such as for instance as automotive vehicles or the like.

The compressed hank of cordage 19 within the inner tube of the nozzle is such that the water introduced through the handle 10 and into such tube will penetrate such hank and 5 will flow readily therethrough. The compressed hank, however, offers obstruction to the free passage of the water and a large proportion of the water will pass outwardly from the inner tube 15 through the perforations 18 10 into the annular space 16 between the tubes and thus be discharged into the spaces indicated at 24 about the lower or discharge end of the nozzle.

Discharging the water into these spaces 24 15 provides for the uniform distribution of the water throughout the body of the mop structure to a much greater extent and much greater uniformity than is provided by mere discharge through a single orifice into the cordage structure.

What I claim to be new is:—

1. A fountain mop comprising a nozzle having concentric tubes forming an annular space therebetween with communication between the interior of the inner tube and the annular space, a compressed mass of cordage disposed within the inner tube, and other cordage secured about the outer tube.

2. A fountain mop comprising a nozzle, 30 having concentric tubes spaced apart to form an annular interval, the inner tube being provided with perforations forming communication from the interior to the annular interval, a folded hank of cordage inserted into the inner tube, and other cordage secured to and surrounding the outer tube.

3. A fountain mop comprising a nozzle embodying concentric spaced tubes forming an annular space therebetween, the inner tube 40 being provided with perforations communicating from the interior of the inner tube to the annular space, a folded hank of cordage inserted into the inner tube, a fastening member inserted diametrically through the tube and through the cordage folded to maintain the cordage within the tube, and other cordage secured about and embracing the outer tube.

4. A fountain mop embodying a distributing fitting comprising inner and outer concentric tubes forming an annular space therebetween, the inner tube being provided with perforations communicating with the annular space, the outer tube being flanged outwardly at its extremity, a hank of cordage inserted 55 into the inner tube, and other hanks of cordage secured upon the exterior of the outer tube and passing over the flanged extremity forming with the interior hank a water distributing space within the cordage.

60 5. A fountain mop comprising a distributing fitting embodying inner and outer spaced concentric tubes forming an annular space therebetween, the outer tube being flanged out at its extremity and the inner tube being provided with perforations communicating with

the annular space, a folded hank of cordage compressed into the inner tube, a diametrically disposed fastening member inserted through the tubes and through the fold of the inner hank, other hanks of cordage secured about the fitting and about the inner hank and forming at the end of the tubes an annular space within the corded structure, and other cordage fastening the several cordage hanks in operative relation.

In testimony whereof I affix my signature.

ENOS WERTZ.
